UNITED STATES PATENT OFFICE.

JOHN M. WELCH, OF HOUSTON, TEXAS.

DEVICE FOR SWIMMING-BELT CONSTRUCTION.

Application filed April 21, 1924. Serial No. 708,072.

To all whom it may concern:

Be it known that I, JOHN M. WELCH, a citizen of the United States, residing at Houston, Texas, have invented a certain new and useful Improvement in Devices for Swimming-Belt Construction, of which the following is a specification.

My invention relates to the construction of swimming or life saving belts of the pneumatic type.

An object of the invention is to provide a means whereby a strong and durable pneumatic belt may be constructed cheaply and easily. It is also desired to construct a belt so shaped and formed as to maintain its shape conforming to the waist line of the wearer and presenting a flat outer face whereby the movements of the wearer will be unincumbered.

The invention involves the strengthening of the belt by longitudinal partitions and the employment of devices whereby said partitions may be readily inserted and secured in position.

Referring to the drawings herewith forming a part of the specification, Fig. 1 is a perspective view of the type of belt to be constructed. Fig. 2 is a transverse section through the belt when it is inflated. Fig. 3 is a top plan of the form employed for inserting the walls or partitions. Fig. 4 is a broken sectional view on line 4—4 of Fig. 3. Fig. 5 is a transverse section showing the belt deflated. Fig. 6 is a top plan view of the enclosing case employed in curing the belt. Fig. 7 is an end perspective view of the form and Fig. 8 is a perspective view of the locking block and Figs. 9 and 10 are similar views of the opposite end of the form and locking means.

This application is a continuation in part of my co-pending application No. 666,082, filed October 2, 1923.

My belt consists of a flattened tube of fabric, impregnated with rubber or similar material impervious to air or water. There are two flattened lengths of the said rubberized fabric, having the edges overlapping at the sides and cemented together to form one continuous tube. It is important to

form the inner section 1 of the belt of fabric cut on the bias. This fabric, when stuck to a rubber lining or when impregnated with rubber, is stretched longitudinally thereof so that it will not wrinkle when rolled or secured to the waist of the wearer. The outer section 2 is of a straight strip of rubberized fabric and is best secured over the inturned edges of the inner section 1, as shown in Figs. 2 and 5. The overlapping edges are cemented firmly together. When thus formed, the inner section 1 will conform to the shape of the wearer's waist and will be entirely free of wrinkles or folds when thus in use, and may also be rolled up into a neat package without causing wrinkles or folds to appear. Cracking of the pneumatic tube will be thus prevented and the belt will last for long periods. The outer section 2 will be approximately flat and will be held thus by partitions in the belt which will be presently described.

In order to prevent the tube from being rounded out as would a vehicle tire when it is inflated, I have formed two partitions 3, connected at their edges at 4 to the inner and outer sides 1 and 2 of the belt. These longitudinal partitions thus formed serve to hold the opposite sides of the belt from being bowed out when inflated, and thus tend to hold the belt in a flattened shape, as shown in Fig. 2. One end of the belt thus formed is closed and sealed together so that there may be no outlet for the air. The opposite end is closed at a point beyond the ends of the longitudinal partitions 3, except for a small opening 5 at one side thereof, in which is tightly cemented a tube 6 by means of which air may be introduced into the belt. The air thus introduced at the end of the belt may find an entrance to any of the three chambers of the belt and will serve to inflate each portion of the belt uniformly. The end of the inflating tube 6 may be provided with a valve 7, allowing air to be forced into the belt, but preventing its outlet therefrom. This tube may preferably be formed of sufficient length to make it possible for the wearer to easily inflate it when it is buckled on, and under ordinary

conditions sufficient air may be blown into the belt by the wearer without the use of an air pump.

The belt may be secured together by any preferred adjustable means, and I have shown straps 11 having buttons 12 thereon to be secured in button holes 9 in any of the plurality of flaps 8. Said straps engage with buckles 10 on the adjacent end 10 of the belt in the usual way.

In constructing this belt, it is necessary to insert between the inner and outer walls 1 and 2 the partition 3. This is done by use of the form shown in Figs. 3 and 4. The form comprises a plurality of strips of light wood or composition adapted to interfit so as to receive the partitions of the belt. The side pieces 14 are rounded at the outer sides on the upper face to conform to the shape of the belt, and have their other sides cut with a mortice or groove 15, preferably V-shaped. The inner strip 16 has its side cut to a tongue or tenon 17 to fit the mortices 15 in the adjacent side pieces. The strips are of the proper length to accommodate the belt desired and will vary in dimensions according to the length of the belt.

The longitudinal sections are held together when desired by retaining plates 19 and 20. The end 21 of the core or form is rounded off slightly so that it may be inserted into or withdrawn from the belt. This end has a notch or recess 22 cut in the assembled form to receive the plate 19. Holes 23 are formed in each of the strips 14 and 16 to receive pins 23' on the plate 19 so as to prevent relative movement and expansion of the form. The plate 20 on the opposite end may be made of metal having pins 24 to fit in openings in the strips to hold them assembled as shown.

The form thus constructed is adapted to include strips of fabric 18 which are preferably cut on the bias to allow them to stretch and conform to the form of the belt when it is secured around the waist of the wearer. These fabric strips are fitted over the edges of the central strip 16 of the form, as shown in Fig. 4, with the edges of the fabric projecting equally on both sides. When the strips of fabric are set in place the form is locked by means of the end plate. The projecting edges of rubberized fabric which may be of raw or uncured rubber are then pressed together to cause them to adhere. The walls may be constructed of separate layers of rubber and fabric adhering together or of one sheet of rubberized fabric.

The inner wall 1 of rubberized bias fabric is first laid down. The form having thereon the strips forming the walls 3 is then placed on the inner wall 1, the edges of the wall being brought around the form and sealed to the outer wall 2. The walls having

uncured rubber will readily adhere when pressed firmly together. The edges of the belt at one end are closed and sealed. The form with the belt thereon is then heat-treated to cure the rubber in the proper 70 shape.

To protect and compress the belt tightly on the form when treated, I may employ an enclosing casing or shell 25, shown particularly in Fig. 6. It is preferably made up of two, cooperating hinged sections of sheet metal shaped to closely enclose the form and belt. These sections are hinged at one side of the form at 26 and have latches of any preferred construction 27 upon the opposite 75 side. The end of the form is allowed to project slightly from the casing, as shown in Fig. 6. The belt is then subjected to heat and pressure to cure the rubber, after which the form is withdrawn from the open end of the belt. The central piece 16 is customarily withdrawn first, thus releasing the other strips. The partitions 3 are in folded shape as shown in Fig. 5, but may be easily expanded as the air is blown in. The tube 6 80 is inserted and the open end of the belt cemented. When this is done the belt is complete. The form thus provided makes it possible to easily and quickly construct the belt in the desired shape with the parts in 85 proper position.

What I claim as new and desire to protect by Letters Patent is:

1. A device for placing longitudinal walls in a pneumatic life belt tube comprising a 100 central section of approximately rigid material having a tongue on each side extending longitudinally thereof, and two side sections having a groove on one side thereof to loosely receive said tongues, said grooves being 105 adapted to receive a strip of flexible material fitting over each said tongue when said tongues are in said grooves, said flexible strip having exposed edges for cementing.

2. A device for placing longitudinal walls 110 in a pneumatic belt tube, comprising a central section of approximately rigid material having its longitudinal sides formed into tongues, side sections having grooves shaped to receive said tongues, said side sections 115 being rounded on their upper outer sides to conform to the shape of the belt.

3. A device for placing longitudinal walls of flexible material in forming pneumatic life belts, comprising a plane central section 120 with longitudinal tongues, and two side sections having grooves adjacent the central section to receive said tongues loosely, said sections being shaped, when assembled, to conform to the shape of the belt.

4. A device for placing longitudinal walls of flexible material in forming pneumatic life belts comprising a plane central section with the lateral edges beveled equally on both sides to form tongues, and side sections 130

having V-shaped grooves to receive said tongues.

5. In a device of the character described, a form comprising flat longitudinal sections 5 adapted to lie side by side, a tongue and groove connection between the adjacent edges of said sections, said connection being

a loose one to include therein strips of flexible material, and means at the ends thereof to hold said sections together. 10

In testimony whereof I hereunto affix my signature this 18th day of April, A. D. 1924.

JOHN M. WELCH.
